HOLDER FOR A PAIR OF EYEGLASSES

Anne A. Pretz, Cleveland, Ohio

Application May 23, 1957, Serial No. 46,313

Term of patent 14 years

(Cl. D57—1)

Fig. 1

Fig. 1 is a front elevational view of a holder for a pair of eyeglasses, embodying my new design;

Fig. 2 is a rear elevational view thereof;

Fig. 3 is a side elevational view thereof;

Fig. 4 is a top plan view thereof; and

Fig. 5 is a cross-sectional view thereof, taken on the line 5—5 of Fig. 1.

I claim:

The ornamental design for a holder for a pair of eyeglasses, substantially as shown.
